UNITED STATES PATENT OFFICE

HAL DEWAIDE, OF PORTLAND, OREGON

SANITARY TOILET-SEAT COVER

Application filed May 29, 1928. Serial No. 281,386.

The object of my invention is to provide a sanitary toilet seat cover made of tissue paper or the like for use in connection with the water flushed toilet now in common use. The cover to be adapted for being readily manufactured in large quantities by cutting a plurality or stack of sheets in a single mechanical stamping operation, so that the seat-cover may be made at a very low cost and 10 sold at a very low price.

Furthermore to provide a sanitary toilet-seat cover which is so constructed that when used an integral portion thereof, which for convenience I will refer to as the carry-off section, will lie in the water of the bowl, and thus when the bowl is flushed the drag of the water on this carry-off section will pull the cover off the seat of the toilet fixture and down the discharge pipe thereof; and that 20 this effect will be assured without fail.

In order to attain the latter result, it is necessary that the said carry-off section of the cover be of substantial length, for otherwise the drag of the water on said section in 25 the flushing of the bowl, may not be sufficient; and indeed, as my own experiences have proved, when the carry-off section of the cover is of insufficient length, the drag exerted on it by the flush of the water may not be sufficient 30 to overcome the suctional resistance of the cover on the toilet seat, and in consequence the cover will not be disposed of except by being first pulled from the toilet seat by hand.

I attain my object in a seat cover consisting of a single sheet of paper or suitable fabric, of convenient size having the central portion corresponding approximately with the opening of the toilet seat, partially severed 35 so that it will provide an integral portion which may be readily separated from the body of the sheet, and, having further an integral, partially severed and readily separable carry-off section, of substantial length when extended, so that said section is adapted to be 40 dropped into the center of the bowl of the toilet before the outlet fixture.

Preferably, I make the said carry-off section a part of said central portion, arranging 45 the severing element of the latter so as to

leave an unbroken hinged section connecting said central portion with the body of the sheet and providing the central portion with a readily separable section lying wholly within the area of said central portion, whereby 55 when said separable portions are separated from the body of the sheet and from each other, the said central portion will drop down into and the said carry-off section will extend therefrom a substantial distance in the center 60 of the bowl and directly before the outlet. Furthermore, it is preferable to make the toilet seat cover with said carry-off part connected to the remainder of the sheet by uncut web sections readily broken and so located 65 as to be broken by the user of the cover in sitting down on the same, after having placed the sanitary cover on the toilet seat. In short, the readily broken web connections make it convenient for the handling of the 70 sheet; and the said web sections should be so arranged that they do not have to be manually broken, but will be broken in the use of the sheet as mentioned, so that the said carry-off portion will automatically drop into the 75 toilet bowl. To this end, the said web sections must be located at the sides of said carry-off part. If located at the end of this part, the connecting web would generally 80 have to be manually broken.

Furthermore the said carry-off part should have ample surface area to insure that the drag of the water in flushing will be sufficient to pull the cover off the seat.

In either construction when the bowl of the toilet seat is flushed, the drag of the water on said carry-off section will pull the seat cover off the toilet seat and dispose of it by carrying it down the discharge pipe of the toilet fixture.

Furthermore as above mentioned, my sanitary cover may be produced by a single operation in this respect differing from all previous sanitary toilet seat covers of which I 95 have any knowledge.

The details of the construction of my sanitary toilet seat cover, I have hereinafter described with reference to the accompanying drawings.

In said drawings:

Fig. 1 shows a perspective view of my seat cover, in its unused state;

Fig. 2 shows a perspective view of my seat cover in its separated or operative position;

Fig. 3 shows a side elevation of a toilet bowl partly in section and illustrates my seat cover, about to be dragged off by the water; and

10 Figs. 4 and 5 show a modification of my invention and illustrates another method of forming the central portion.

Referring now to Figs. 1, 2 and 3, my invention comprises a more or less rectangular sheet *a* of suitable, light and economical paper, as tissue paper, cut as at *b* by stamping to form a central portion *c* conforming more or less to the contour of the toilet seat, except at *b'* which is uncut and serves to connect the portion *c* thus formed to the outer portion of the sheet. Smaller uncut sections *b*² are also provided which are easily severable, but hold the section *c* in place until the seat cover is to be used.

25 Another similar cut *d* is made, entirely within the portion *c*, also provided with an uncut section *c'* to connect the portion *c* so formed to the portion *c* oppositely to the uncut portion *b'* of the portion *c*, and easily 30 severable uncut connecting sections *c*² are provided, similar to the severable sections *b*² of the portion *c*.

The uncut connecting webs *b*² are located at the sides of the sheet, and are thus directly 35 subject to, and broken by the pressure of the person in sitting down on the seat, after the cover has been placed on the toilet seat.

In use my cover will be arranged on the seat as illustrated by Figs. 2 and 3, with the 40 uncut connecting sections *b*² at the sides; whereby the latter, as well as the temporary web connection *c*² of the portion *c* will be readily broken by the user as described.

The portions *c* and *e* thus detached will 45 become arranged as shown by Figs. 2 and 3 so as to lie in the water of the bowl, and the flushing of the latter will cause the cover to be pulled off the seat, and automatically disposed of, without any handling of the cover.

50 It will be noted that the portion *e* is given considerable width which is done to expose ample surface to the drag of the water. It will be further noted that the parts *c* and *e*, and the connection of the part *c* to the main 55 portion of the cover, also the connection of the part *e* with the part *c* are so arranged as to take advantage of the full tensile strength of the paper.

Further, by this construction my toilet seat 60 cover is adapted to have the carry off portion *e* not only lie in the water but in the center of the bowl directly before the outlet 5 so that the drag of the water will be certain to carry away the cover, and there will be no 65 tendency for the portion *e* to cling to the

sides of the bowl and thus prevent the seat cover from being carried away.

Referring to Figs. 4 and 5, I have shown a modification of my sanitary seat cover, cut at *2*^b to form a central section *2*^d more or less of the shape of the toilet seat. The said cut *2*^b is prolonged as at *2*^c, thru the center of the portion *2*^d, thus forming the carry-off section *2*^g. Small uncut but easily severable portions *2*^f are provided, which when broken will permit the central portions *2*^d and *2*^g to hang down into the water and be dragged away as before described by the flushing of the toilet bowl.

I claim:

1. A sanitary toilet-seat cover comprising a sheet having a central oval portion readily detached to form a central opening in said sheet, said central portion being connected to the sheet at one end, and by breakable connections at its sides to the sides of the sheet, said central portion comprising two members adapted to be extended substantially end to end, whereby upon breaking said breakable connections, said central portion may be arranged to form an elongate strip of substantial length, pendent in, and lying along the longitudinal center of the bowl of the toilet fixture, and in front of the outlet of said bowl, thus subjecting said strip to the drag of the water flushing the bowl, and in that way removing and disposing of the sanitary cover.

2. A sanitary toilet-seat cover comprising a sheet having a central portion partially detached to form a central opening in said sheet, said central portion comprising an annular piece connected to the sheet at one end, and by breakable connections at its sides to the sides of the sheet, and an inner piece encompassed by said annular piece and connected to the latter at one end and at the other end by a readily breakable connection, whereby, upon breaking said breakable connections, the said annular piece and inner piece of said central portion may be arranged to form an elongate strip of substantial length pendent in and lying along the longitudinal center of the bowl of the toilet fixture, and in front of the outlet of said bowl, thus subjecting said strip to the drag of the water flushing the bowl, and in that way removing and disposing of the sanitary cover.
